PAPER-FEEDING MECHANISM.

1,196,851.

Specification of Letters Patent.

Patented Sept. 5, 1916.

Application filed February 20, 1915. Serial No. 9,534.

To all whom it may concern:

Be it known that I, RUFUS A. FREEMAN, a citizen of the United States, residing at Flushing, in the county of Queens and State of New York, have invented certain new and useful Improvements in Paper-Feeding Mechanism, of which the following is a specification, reference being had therein to the accompanying drawing.

10 This invention relates to paper-feeding mechanism, and has reference more particularly to that type of mechanism in which the pile of sheets is acted on by a combing device, which partially separates the topmost sheets one by one and presents them in succession to a delivery mechanism by which the sheets are conveyed away.

The main feature of novelty of my present invention relates to the means for controlling the action of the combing device on the sheets, the said means being controlled in its operation by the successive sheets separated and advanced by the combing device, and the said controlling means operating through the medium of improved devices to be more fully described hereinafter, to automatically disengage the combing device from the sheet when the latter reaches a position where it is operated on by the delivery mechanism, and means operating to cause the combing device to engage the next sheet of the pile.

My invention is directed also to means for insuring a uniform thickness or height 35 of the pile of sheets fed to the action of the combing device, at the point where the combing device acts thereon, mechanism of improved form being employed which is controlled in its action by the thickness of 40 the pile and which automatically controls the means for feeding the pile forwardly, in such manner that the feed will be arrested if the thickness of the pile becomes too great for proper action of the combing device, and will be resumed when the normal 45 and proper thickness of the pile is restored.

In the more specific embodiment of my invention, as shown in the accompanying drawings, a traveling feeding bed is provided, on which the pile of sheets is supported and advanced to the action of the combing device, and the combing device is

in the form of a rotary drum with peripherally arranged sheet engaging elements thereon, which acts on the topmost sheet of the pile, partially separates the same from the next sheet beneath, and advances the separated sheet to the action of the delivery mechanism.

The combing device is supported in such 60 manner that it is movable up and down, respectively out of and into engagement with the topmost sheet of the pile, which movements of the drum are effected through the medium of a clutch mechanism comprising 65 a friction member and a coöperating traveling friction element, the said friction member being movable with the up and down movements of the drum, and operating, when engaged with the traveling friction 70 element, to raise the drum; and operating when disengaged from said element, to permit the drum to descend. The friction member is controlled in its actions by means of a movable controlling member, with 75 which the forward end of the sheet advanced by the combing device, coöperates in such manner that when the sheet engages said member and the latter is moved thereby, the friction member will be caused to engage 80 with the traveling friction element, and the combing device will be elevated out of engagement with the sheet, and will permit the latter to be conveyed away by the delivery mechanism, the return of the combing device for engagement with the next sheet of the pile, being effected automatically and through means which act to disengage the friction member from the traveling friction element at a predetermined 90 time. Two combing devices are preferably employed to operate on the same sheet, which devices are thrown out of engagement with the sheet by the independent operation of their respective controlling members; whereby the advancing sheet will be 95 presented squarely and evenly to the action of the delivery mechanism.

The traveling bed which supports the pile of sheets, is advanced by a feeding mechanism, and coöperating with this mechanism is a controlling device which rests upon the pile adjacent the point where the combing devices act, and which controlling device

acts automatically to arrest the action of the feeding mechanism when the thickness of the pile becomes too great for the proper operation of the combing devices, the interruption in the action of the feeding mechanism being maintained, until, by the continued action of the combing devices, the proper thickness of the pile has been restored, whereupon the controlling device 10 will be operated to permit the resumption of the action of the feeding mechanism.

In the accompanying drawings, I have shown one form of embodiment of my invention by way of example, embodying the 15 features of construction above set forth. It will be manifest however, that the constructional details of the mechanism may be variously modified and changed by the skilled mechanic without departing from the limits 20 of my invention; and it will be understood that the invention is not limited to any particular form or construction of the parts, except in so far as such limitations are specified in the claims.

25 In the accompanying drawings: Figure 1 is a top plan view of my improved mechanism. Fig. 2 is a side elevation of the same. Fig. 3 is a vertical sectional elevation, on an enlarged scale, on the line *a—a* 30 of Fig. 1, showing the combing device lowered in action. Fig. 4 is a similar view showing the combing devices raised out of action. Fig. 5 is a horizontal sectional plan view of one of the combing devices on the line *b—b* of Fig. 3. Fig. 6 is a vertical 35 sectional elevation of the same on the line *c—c* of Fig. 4.

Referring to the drawings: The operative parts of my improved mechanism are 40 mounted in and sustained by a flat frame, comprising parallel side frame-bars 1 and 2, connected together at their front ends by a transverse frame-bar 3. Sustained by this frame, is a traveling feeding bed for the 45 pile of sheets, which bed in the present instance comprises a series of endless feeding belts 4, extending longitudinally of the frame, side by side, and supported at the front and rear respectively, by a series of 50 pulleys 5 and 6 carried by transverse shafts 7 and 7^a journaled in suitable bearings in the side frame-bars, respectively at their opposite ends. The pile of sheets A is 55 placed on the feeding belts, and motion being imparted to the forward shaft 7, by mechanism to be more fully described hereinafter, the pile will be fed forwardly, and the topmost sheet will be presented to the action of the overlying combing devices 8, 60 by which the topmost sheet will be advanced and partially separated from the next sheet beneath, and presented to the action of the delivery mechanism B by which it will be conveyed away from the 65 machine.

The combing devices, in the form of the drums 8^a with the peripherally arranged sheet engaging elements, as before mentioned, are arranged at the opposite sides of the feeding bed, in position to act on the 70 topmost sheet of the pile, and as these devices are identical in form and construction, and are independently operable, a description of one will suffice. The drum is mounted fixedly on a shaft 9 journaled in a sleeve 10 fixed to the rear end of a supporting arm 11, the opposite end of which is loosely mounted on a bushing 12 loosely surrounding a rotary main operating shaft 13 extending transversely above and across 80 the feeding bed, and mounted at its ends in suitable bearings in standards 14 and 15 extending upwardly from the side frame-bars near their front ends, the construction being such that the two combing drums may 85 move up and down independently of each other, respectively out of and into engagement with the top sheet of the pile, their supporting arms 11 in such motions, swinging about the axis of the operating shaft 13. 90 A cylindrical casing 16 surrounds the bushing, and is provided with a central hub which encircles the outer end of the bushing, and to which it is firmly fixed, the sleeve 10 on the arm 11 being extended laterally through a slot 17 formed in a rearward extension of the casing, the upper end of which slot serves as a stop to limit the 95 upward movement of the arm and consequently the upward movement of the combing drum. The casing is supported at its top, on a horizontal transverse bar 18 extending parallel with and above the shaft 13 and fixedly sustained at its ends in the standards 14 and 15. The casing is provided with a boss containing an opening surrounding the bar and clamped fixedly thereto by means of a set-screw 19, the construction being such that the casing may be 100 adjusted longitudinally of the bar to different positions transversely of the feeding bed, for the purpose presently to be described. The shaft 9 is extended beyond the end of the sleeve 10, where it has fixed to it a driving pinion 20, engaged by a 105 spur gear 21 connected to shaft 13 by a set-screw 22, in such manner that the gear may be adjusted longitudinally of the shaft, while being subject to the rotary motion of the shaft. The arm 11 is engaged on its 110 under side by the rear arm 23 of a two-armed lever 24, mounted between its ends to rock on the bushing 12.

The friction member before alluded to, is 115 in the form of an upright clutch dog 25, which is pivotally mounted between its ends on a horizontal stud 26 extending laterally from the forward arm 24^a of the two-armed lever, the upper end of which dog is provided with a segmental friction shoe 27 120

which, in the pivotal motions of the dog about its axis, is adapted to be moved into and out of engagement with the annular friction element surface 28 formed on the 5 interior of the rim of the spur gears 21. When the clutch dog is rocked, and its friction shoe caused to engage with the friction surface 28, the latter surface moving in the direction of the arrow in Fig. 3 will carry 10 the clutch dog with it, and will swing the forward arm 24^a of the two-armed lever 24 downwardly, which action, elevating the rear arm of said two-armed lever, will, owing to the engagement of said rear arm with 15 the drum-supporting arm 11, elevate the latter and raise the combing drum from the position shown in Fig. 3 to that shown in Fig. 4. The drum will be held elevated as long as the friction shoe maintains engagement 20 with the annular friction surface, the latter, in the rotation of the spur gear, slipping past the contacting surface of the friction shoe, and maintaining the combing drum in its upper position, with the sleeve 25 10 engaging the upper end of the slot 17 in the cylindrical casing. The clutch dog is rocked on its axis to disengage the friction shoe from the annular friction surface, by means of a cam 29 carried by the hub of 30 the spur gear and rotatable therewith, which cam is adapted to engage a roller 30 on the lower end of the clutch dog, and by such engagement, operating to rock the clutch dog on its axis and to positively disengage 35 the friction shoe from the annular friction surface. When thus disengaged, the weight of the drum will cause it to descend and engage the top sheet of the pile.

The engagement of the clutch dog with 40 the annular friction surface is controlled by the movable controlling member before alluded to as coöperating with the front edge of the sheet advanced by the combing device, which movable member is indicated by the reference numeral 31 (Figs. 3 and 4). This movable member is in the form of an upright lever, pivoted between its ends, as at 32, to the cylindrical casing 16 on a horizontal transverse axis, the upper arm 33 45 of the lever extending upwardly into the casing and alongside the forward arm 24^a of the two-armed lever 24 and being provided with a latch 31^a. The lower arm 34 of the lever 31 curves forwardly and terminates in a horizontal finger 35, which extends above and in close proximity to the upper side of a horizontal rotary take-off roller 36 mounted in suitable bearings in the side bars of the frame at their front ends, the arrangement being such that the front edge of the sheet advanced by the combing device, will pass between the under side of the finger 35 and the upper side of the take-off roller, which latter is rotated continuously by the means presently to be de-

scribed, in the direction of the arrow in Figs. 3 and 4. This take-off roller forms one of the members of the delivery mechanism, the other member being formed by two vertical pressure rolls 37, overlying the take-off roller and movable up and down relatively thereto so as to hold the presented sheet in contact with the take-off roller to enable the latter to convey it away. The pressure rolls are carried on the forward 70 ends of two arms 38 fixed to a horizontal transversely extending rock shaft 39 mounted in suitable bearings in the frame standards, the said shaft being rocked periodically, in the manner to be more fully 75 described later on, in order to cause the pressure rollers at the proper time, to descend and press the presented sheet onto the take-off roller.

The take-off roller is grooved peripherally, and the under side of the finger 35 is correspondingly grooved so that when the finger is in its lower position, the ribs between the grooves thereon will enter into the grooves between the ribs on the take-off 80 roller, this relation of the finger and roll being permitted when there is no sheet between them. When, however, a sheet enters between the finger and roller, it will lift the finger, and the latter will be maintained by 85 the sheet in raised position.

The latch 31^a on the upper end of the arm 33 of lever 31 is adapted to engage over a horizontal shoulder 39^a projecting rearwardly from the clutch dog, and when so 90 engaged, it will hold the dog with the friction shoe in its rearward position and disengaged from the annular friction surface as shown in Fig. 3, this being the position of the parts when the finger 35 of the lever is 95 in its lower position on the take-off roller, with the ribs and grooves interengaging, and with the combing drum in its lowered position in engagement with the topmost sheet of the pile. Lever 31 in this position, 100 therefore, holds the clutch dog disengaged from the annular friction surface, and the combing drum rotated by the spur gear, acts on the topmost sheet, advances the same and enters its forward edge between the finger 105 35 and take-off roller, the pressure rollers 37 during this action being in elevated position. As the edge of the sheet enters the bite between the finger and roller, the finger 110 will be slightly elevated, and the lever 31 115 rocked on its axis, which action will swing the latch 31^a to the rear and will release the clutch dog, whereupon the preponderating weight of the upper end of the clutch dog 120 will swing this end forwardly and cause the 125 friction shoe to engage with the annular traveling friction surface. As the friction surface advances, it will take frictional hold of the friction shoe, and will rock the two-armed lever 24 on its axis, and this action 130

will elevate the combing roll in the manner previously described, and will disengage the same from the sheet. At the moment that the front edge of the sheet passes between the take-off roller and overlying finger and actuates the latter, the pressure rolls 37 descend as will be presently described, and pressing the sheet against the rotating take-off roller, the latter will convey the same from the machine. During this action, and while the sheet is being conveyed away by the take-off roller, the high part of cam 29 engages roller 30 on the clutch dog and the latter is swung on its axis and its friction shoe disengaged from the annular friction surface; whereupon the weight of the combing drum will cause it to descend and effect engagement with the next sheet. By this time the preceding sheet has passed from between the finger 35 and take-off roller, and the finger descends, and the ribs thereon enter the grooves in the take-off roller, which action will throw the upper arm 33 of the lever forwardly and cause its latch 31^a to engage over the shoulder 39^a on the clutch dog and lock the same out of engagement with the moving friction surface, the engagement of the latch with the shoulder occurring while the high part of the cam 29 is holding the clutch dog in the position shown in Fig. 3. The next sheet is now advanced by the combing device, and entering between the finger and take-off roller, the finger will be elevated as before, and the latch 31^a disengaged from the clutch dog, and the foregoing operations will be repeated, resulting in the disengagement of the combing device from the sheet, and the delivery of the latter from the machine by the delivery mechanism. It is seen, therefore, that the lever 31, by coöperating with the sheet advanced by the combing device, will, when this sheet arrives at the point where it is subject to the action of the delivery mechanism, initiate the action of mechanism which will automatically cause the combing device to disengage from the advanced sheet, the result being that the combing device will advance the sheets successively to the action of the delivery mechanism, and will release or disengage the successive sheets as they are in turn received by the delivery mechanism. By reason of the relative form and arrangement of the coöperating engaging surfaces of the latch 31^a and shoulder 39^a, which surfaces extend substantially in line with the back and forth movement of the latch, but a slight pressure against the under side of the finger 35 will be required by the advancing sheet, to actuate the latch to release the clutch dog. Consequently the edge of the sheets will trip the lever with certainty and uniformity, and without liability of buckling or becoming displaced.

It will be noted from the foregoing de-

scription that the swinging arm 11 supporting the combing drum, has a movement relatively to the two-armed lever 24 which supports the clutch dog. The purpose of this particular construction is to prevent any vibration or jar, to which the arm 11 might be subjected in the rotary motion of the combing drum, from releasing the clutch dog when held disengaged by the latch on lever 31. As above stated, the coöperating surface of the latch on the lever and shoulder on the dog extending substantially in the line of movement of the shoulder, there would be liability, if the two-armed lever 24 were connected to the swinging lever 11, of the vibration or jar of the latter releasing the dog before the sheet being acted on by the combing device, reached the take-off roller. Therefore by sustaining the combing drum and dog, respectively by separate parts, that is, parts capable of relative motion, the clutch dog will not be affected by the arm, and there will be no liability of accidental engagement of the clutch dog with the annular friction surface, and the consequent elevation of the combing drum prematurely. When the supporting arm descends to carry the drum into engagement with the sheet, the weighted rear arm 23 of the two-armed lever also descends, and continues to descend after the drum engages the sheet, the continued descent of arm 23, causing it to separate from arm 11, it finally coming to rest against a stop lug 23^a on the interior of the casing 16. In this position of arm 23 latch 31^a will engage the clutch dog and the arm being disengaged and separated from supporting arm 11, there will be no liability of the premature release of the clutch dog.

The relative movement of the clutch dog to carry the friction shoe into engagement with the annular friction surface, is limited by a vertical stop screw 40 threaded in the forward arm 24^a of the lever 24, with its upper end in position to be engaged by a laterally extending lug 41 on the clutch dog when the dog is swung so as to effect engagement with the annular friction surface. By adjusting this screw, the degree of frictional engagement between the shoe and annular surface may be controlled so as to maintain a relation of the parts which will insure their effective and proper coöperation.

By supporting the casing 16, which encloses the operating mechanism for the combing devices, adjustably on the transverse bar 18, and by connecting the spur gear 21 with the shaft 13 for longitudinal adjustment thereon, the two combing devices may be adjusted independently of each other transversely with reference to the feeding bed. The purpose of this adjustment is to provide for the proper operation of the combing devices on sheets of different sizes,

the said devices being adjusted nearer the center of the bed for narrow sheets, and farther outward for wider sheets.

The shaft 13 is, in the present instance, 5 the main operating shaft, from which the various operative parts of the mechanism are driven and timed, and motion is conveyed from shaft 13 to the take-off roller 36 by means of a pinion 42 on shaft 13, 10 which meshes with a pinion 43 journaled on the frame of the machine, which pinion in turn engages a gear 44 fixed to and rotatable with the take-off roller.

The up-and-down-movable pressure rolls 15 37, are actuated by means of a cam 44^a fixed to the end of shaft 13 and engaging a roller 45 on the upper end of an arm 46 fixed at its lower end to the end of the rock shaft 39 which carries the pressure rolls, the shape 20 of the cam 44^a being such that for every revolution of the shaft 13, the pressure rolls will be moved upwardly and downwardly to coöperate with the take-off roller 36 as previously described. Shaft 13 also drives 25 the feeding bed, by imparting to the shaft 7 carrying the forward supporting pulleys for the endless bands 4, an intermittent step-by-step movement so as to impart a corresponding feeding motion to the pile of 30 sheets. This driving action is effected in the following manner: A ratchet wheel 47 is fixed to the end of shaft 7, and is acted on by a driving pawl 48 pivoted to an upright vibratory lever 49 mounted loosely at 35 its lower end on the shaft 7 at the outer side of the ratchet wheel, the forward motion of the lever 49 causing the pawl to engage the ratchet teeth and advance the ratchet wheel, and consequently rotate the shaft 7, 40 and the return movement of the vibratory lever causing the driving pawl to engage the next tooth on the wheel. Lever 49 is vibrated by means of a cam 50 fixed to shaft 13 at the inner side of the cam 44, 45 which cam 50 engages a roller 51 on the outer end of a reciprocating driving member in the form of a yoke-frame 52, having a slot 53 therein which straddles shaft 13, the rear end of the said yoke being jointed, 50 as at 53^a, to the upper end of the vibratory lever 49. The form of cam 50 is such that in each revolution of the shaft 13, it will thrust the yoke frame forwardly endwise, which action will swing lever 49 in a corresponding direction, and will cause the driving pawl 48 thereon to advance shaft 7 one step, the lever being moved rearward for another hold on the ratchet wheel by means of a spring 49^a fixed at its ends to the lever 55 and frame respectively. The continuous rotation of the operating cam will thus act to turn shaft 7 intermittently, and advance the feeding belts step by step.

The control of the feeding movement of 65 the belts by the thickness of the sheet pile,

is effected by interrupting the movement of the yoke frame imparted thereto by cam 50. This is effected by means of a finger 54 fixed at its upper end to a horizontal transverse rock shaft 55 mounted in bearings in the 70 standards 14 and 15. The finger at its lower end, floats on the surface of the sheet pile, and it has connected with its upper end, a forwardly extending arm 56, the forward extremity of which normally, and when the 75 sheet pile is of the proper thickness, stands below and out of the path of a block 57 on the yoke frame, in which position of the parts, the yoke frame is free to be moved endwise by its cam and will impart a vibratory motion to lever 49. When, however, the thickness of the pile increases to an improper point, finger 54 being raised, will lift arm 56 and move it into the path of block 57, and the end of the arm will, in 80 this position, act as a stop for the yoke and will prevent it from being moved rearwardly by its spring, and the cam will rotate idly with the lever held in its forward position without imparting motion to the 85 same, and consequently the feeding bands will remain at rest. When by the removal of the successive sheets and their delivery, the proper thickness of the sheet pile has been restored, the finger 54 moving down, 90 will again lower arm 56 out of the path of block 57 on the yoke frame, and the latter being released, it will as before, be operated by its cam, and the feeding movement of the 95 belts will be resumed. It will be noted therefore, that by the mechanism described, the 100 advance of the sheet pile to the action of the combing devices is automatically controlled by the thickness of the pile, at the point where the combing devices act thereon, the increase of the thickness of the pile beyond its normal and proper limits, acting to automatically check the feeding movement, which movement will be automatically resumed, when by the removal of the sheets 105 due to the continued action of the combing devices, the pile has been restored to its normal and proper thickness.

In the operation of the machine, the parts are so timed that for each revolution of 115 shaft 13, the clutch dog will be operated by the high part of cam 29 to disengage the friction shoe from the annular friction surface, and this action is so timed in relation to the delivery of the sheet, that the latch 120 on lever 31 will be permitted to move forward in position to engage the shoulder on the clutch dog when the low part of the cam engages the roller 30 and thus releases the clutch dog, the shoulder on the latter being 125 then engaged by the latch 31^a. It is seen, therefore, that by the continued rotation of the operating shaft 13, the combing devices will alternately engage and disengage from the sheets, and will advance them success- 130

sively to the action of the delivery mechanism, the combing devices remaining in action on a sheet until it has been advanced within reach of the delivery mechanism, and 5 then disengaging from the sheet, and being held disengaged until the first sheet has been conveyed far enough not to interfere with the advance of the second sheet, and then lowered again into action on the second 10 sheet, the disengagement of the combing device from the second sheet being effected automatically, when the latter reaches a point where it will be acted on by the delivery mechanism. As a result of these repeated 15 sequences of operation, the sheets are never acted on simultaneously both by the combing devices and the delivery mechanism, but said mechanisms operate on the sheets individually, that is to say, when the 20 delivery mechanism is acting on one sheet, the combing device is acting on the next sheet, and when this latter sheet is taken up by the delivery mechanism, it is freed from the action of the combing device. This insures 25 a uniform feed of, and the delivery of the sheets, in a speedy manner and without danger of tear or buckling.

By reason of the fact that the two combing devices and their associated controlling 30 members are independently mounted and controlled, the sheets will be advanced and presented squarely to the action of the delivery mechanism.

Having thus described my invention, what 35 I claim and desire to secure by Letters Patent is:

1. In a paper-feeding mechanism, the combination of a combing device operable to advance the sheets, and movable out of engagement with the same, a traveling friction element, a friction member adapted to be engaged with and moved by said friction element, operative connections between the friction member and the combing device, 40 whereby the movement of said member by the traveling friction surface will move the combing device out of engagement with the sheet, and releasable controlling means for positively holding said friction member out 45 of engagement with the friction element, said means adapted to be released by the advancing sheet.

2. In a paper-feeding mechanism, the combination of a combing device operable to advance the sheets and movable out of engagement with the same, a traveling friction element, a friction member adapted to be engaged with and moved by said friction element, and tending normally to move into engagement with the same, operative connections between the friction member and the combing device, whereby the movement of said member by the friction element will move the combing device out of engagement 55 with the sheet, and a movable controlling de-

vice coöperating with said friction member and holding the same out of engagement with the friction element, said controlling device adapted to be moved by the advancing sheet to release the friction member. 70

3. In a paper-feeding mechanism, the combination of a combing device operable to advance the sheets, and movable out of engagement with the same, a traveling friction element, a friction member adapted to be engaged with and moved by said friction element, operative connections between the friction member and the combing device, whereby the movement of said member by the friction element will move the combing device out of engagement with the sheet, and a movable controlling device in position to be engaged and moved by the advancing sheet, and provided with a locking surface adapted to engage a corresponding surface on the friction member and hold the same out of engagement with the friction element, said engaging surface extending in the general direction of the movement of the controlling device. 80

4. In a paper-feeding mechanism, the combination of a combing device operable to advance the sheets, and movable out of engagement with the same, a traveling friction element, a friction member adapted to be engaged with and moved by said friction element, operative connections between the friction member and the combing device, whereby the movement of said member by the friction element will move the combing device out of engagement with the sheet, and a controlling device having a latch to engage the friction member and hold it out of engagement with the friction element, and being provided with a tripping finger adapted by the action of the advancing sheet to trip the latch and release the friction member. 95

5. In a paper-feeding mechanism, the combination of a combing drum operable to advance the sheets, a swinging supporting arm on which said drum is mounted and by which it is moved out of engagement with the sheet, a traveling friction element, a lever movable relatively to the supporting arm and engaging the latter to swing the arm, a friction member mounted on the lever and adapted to be engaged with and moved by the friction element to swing the supporting arm, and means operated by the advancing sheet for controlling the engagement of the friction member with the friction element. 100

6. In a paper-feeding mechanism, the combination of a combing drum operable to advance the sheets, an arm giving support to the combing drum and mounted to swing on an axis to disengage the combing drum from the sheet, a traveling friction element, a two-armed lever mounted to rock on the 115 120 125 130

axis of the supporting arm and movable relatively to said arm, one of the arms of the lever being in position to engage the supporting arm, a friction member mounted on 5 the other arm of the lever and adapted to be engaged with and moved by the friction element, and means operated by the advancing sheet for controlling the engagement of the friction member with the friction element.

7. In a paper-feeding mechanism, the combination of a rotary driving gear, a supporting arm swingable on the axis of said gear, a rotary combing drum mounted on 15 said arm, a driving pinion connected with the combing drum and engaged by the gear, a traveling friction element concentric with the axis of the driving gear, a friction member operatively connected with the supporting 20 arm and adapted to be engaged with and moved by the friction element to swing the arm and disengage the combing drum from the sheet, and means operated by the advancing sheet for controlling the engagement of 25 the friction member with the friction element.

8. In a paper-feeding mechanism, the combination of a rotary driving gear having an annular friction surface, a supporting 30 arm swingable on the axis of the gear, a rotary combing drum mounted on said arm, a driving pinion connected with the drum and engaged by the gear, a friction dog operatively connected with the supporting arm 35 and movable into and out of engagement with the annular friction surface, and means operated by the advancing sheet for controlling the engagement of the friction member with the friction surface.

40 9. In a paper-feeding mechanism, the combination of a combing drum operable to advance the sheets, a supporting arm on which said drum is mounted, said arm being movable to disengage the combing drum 45 from and engage the same with the sheets, a movable lever adapted to engage the supporting arm, a friction member carried by the lever, a traveling friction element engaged by the friction member and operating 50 when so engaged to move the lever and operate the supporting arm to disengage the combing device from the sheet, means controlling the engagement of the friction member with the friction element, and means 55 for disengaging the friction member from the friction element to allow the supporting arm to move the combing device into engagement with the sheet, the said lever adapted when the combing drum is thus moved, to move relatively into and out of engagement with the supporting arm.

60 10. In a paper-feeding mechanism, the combination of a combing drum operable to advance the sheets, a supporting arm on which said drum is mounted, said arm being

movable to disengage the combing device from and engage the same with the sheets, a movable lever adapted to engage the supporting arm, a friction member carried by the lever, a traveling friction element engaged by the friction member and operating when so engaged to disengage the combing drum from the sheet, means for controlling the engagement of the friction member with the friction element, means for disengaging the friction member therefrom to allow the supporting arm to permit the combing drum to move into engagement with the sheet, said lever adapted when the combing drum is thus engaged to move out of engagement with the supporting arm, and means for limiting said latter movement of the lever.

75 11. In a paper-feeding mechanism, the combination of a combing device operable to advance the sheets and movable into and out of engagement with the same, a lever operable to disengage the combing device from the sheets, a traveling friction element, a friction member movably mounted on the lever and adapted to engage and be moved by the friction element, an adjustable stop device on the lever in position to be engaged by the friction member, and means for controlling the engagement of the friction member with the friction element.

80 12. In a paper-feeding mechanism, the combination of a combing device operable to advance the sheets and movable into and out of engagement with the same, a traveling friction element, a friction member adapted to engage with and be moved by the friction element to disengage the combing device from the sheets, a latch co-operating with the friction member to hold the same out of engagement with the friction element, means controlled by the advancing sheet to trip the latch to permit the friction member to engage with the friction element, whereby the 85 combing device will be disengaged from the sheet, means for disengaging the friction member from the friction element to permit the combing device to engage with the sheet, and a delivery device adapted to act on the sheet when disengaged by the combing device, said several mechanisms being so timed that the friction member will be disengaged from the friction element and in position to be engaged by the latch when the sheet leaves the delivery mechanism.

90 13. In a paper feeding mechanism, the combination of an endless feeding belt for supporting the sheet pile, a driving pulley around which said belt passes, a ratchet wheel movable with said pulley, a vibrating lever extending upwardly above the feeding belt and provided with a pawl engaging the ratchet wheel to drive the same, a rotary cam mounted above the feeding belt, a reciprocating yoke frame jointed to the upper 95 100 105 110 115 120 125 130

end of the driving lever and engaged by the cam, a gravitating finger mounted above the belt to rock on a horizontal transverse axis and extending downwardly and resting on the sheet pile, and an arm fixedly connected with the finger and extending upwardly therefrom, said arm being movable by the finger into and out of the path of the yoke

frame according to the thickness of the sheet pile.

In testimony whereof, I have affixed my signature in presence of two witnesses.

RUFUS A. FREEMAN.
